HEARTH TYPE FURNACE

Henry W. Beecher, Seattle, Wash.; Blanche Cameron Beecher and Henry Ward Beecher, Jr., executors of said Henry W. Beecher, deceased

Application August 29, 1949, Serial No. 112,907

4 Claims. (Cl. 122—2)

1

This invention relates to furnaces, and more particularly to hearth-type furnaces designed for use in burning wood or similar fuels under water tube boilers.

To burn wood waste fuel efficiently in a furnace, the following conditions should be provided:

First—A large area of fuel should be exposed to furnace temperatures in order to effect evaporation of moisture in the fuel and the distillation of volatiles.

Second—Fresh fuel should progressively enter the furnace in such a manner that it does not cover the fuel previously fed thereto, and the fuel bed should move gradually from a zone of distillation into a zone in which only the fixed carbon remains. There should be a minimum overlaying of wet fuel.

Third—Pre-heated air should be forced through the green fuel to drive off volatiles and moisture, and additional pre-heated air should pass through the zone of incandescent carbon at such a rate that a mixture of carbon monoxide and carbon dioxide is formed; the former being converted to carbon dioxide in the presence of over-draft air.

Fourth—Over-draft air should be so applied as to create turbulence and intimate mixing with the volatiles.

It is the principal object of this invention to provide a furnace, complying with the above conditions, for the burning of normally slow burning cellulose products of high moisture content, for example, chopped up wood waste frequently referred to as hogged fuel, with or without the aid of supplemental fuel, and by my improvements, to effect the burning of the fuel in such a way as to stimulate the distillation process by which moisture is evaporated therefrom and the hydro-carbon gasses are driven off and burned in gaseous form.

It is also an object of my invention to provide a furnace with a sloping, watercooled hearth or grate, comprising tubes through which a portion of the boiler water is circulated; the tubes being so disposed as to provide restricted passages between them for the flow of pre-heated forced-draft air through the fuel bed.

A further object of my invention is to obtain better burning conditions and to insure the progression of the fuel bed downward along the hearth. This is accomplished by dividing the hearth area into a plurality of zones with controlled admission of pre-heated, forced-draft air to the fuel bed over each of the zones.

2

A still further object of my invention is to provide a furnace hearth of the above character having sufficient area that the upper end zone thereof can advantageously be left partially or entirely uncovered by the fuel bed, for the introduction therethrough of pre-heated forced-draft air, in regulated amount, to supplement air introduced through other over-draft air openings. Its admittance in this way and at this location creates greater turbulence and a better mixing of air with combustible gases.

Another object of my invention is to provide a hearth furnace embodying the novel features above mentioned, and also including means for so maintaining and burning the fuel bed that it will gradually progress downward from the fuel inlet and avoid the overlaying of incandescent carbon by entering fuel and avoid the disadvantages that are incident to such overlaying.

It is important in a furnace that excess air be kept to a minimum in order to secure maximum efficiency. It is also important, for like reason, to insure that as large a percentage as possible of the air entering the furnace be pre-heated. Therefore, it has been an object of this invention to provide means for the feeding of fuel to the hearth through a fuel seal that limits the cold air admitted with the fuel and prevents injecting cold air into the furnace through the feeding opening.

Further objects and advantages of the invention reside in the improved details of construction of the discharge end portion of the hearth that prevents adherence of slag, and in the provision of jets for the delivery of pre-heated air to the toe of the fuel bed to insure the most complete burning.

Still further objects of my invention reside in the details of construction and relationship of the various parts as used in the preferred and in the alternative forms of construction, hereafter described.

In accomplishing the objects of my invention, I have provided the improved details of construction, the preferred forms of which are illustrated in the accompanying drawings, wherein—

Fig. 1 is a cross-sectional view of a portion of a furnace embodying the improvements of the present invention.

Figs. 2 and 3 are sectional details showing alternative constructions at the lower end portion of the hearth.

Fig. 4 is a horizontal section, taken substantially on the line 4—4 in Fig. 1, with some of the hearth tubes broken away.

Fig. 5 is an enlarged, sectional view taken on line 5—5 in Fig. 4, showing a part of the hearth and one of the zone forming plenum chambers for application of pre-heated, forced-draft air to that zone of the hearth.

Fig. 6 is an enlarged, cross-section taken on line 6—6 in Fig. 5, showing the close spacing of hearth tubes.

Fig. 7 is a detail in perspective, illustrating an alternative hearth construction.

Fig. 8 is detail in perspective of yet another alternative hearth construction.

Fig. 9 is a cross-sectional view of a portion of a furnace, showing an alternative fuel feeding system.

Fig. 10 is a sectional detail showing an alternative construction of that portion of the furnace above the lower end portion of the hearth.

Fig. 11 is a cross-sectional detail showing a hearth with side wall tubes.

Fig. 12 is a vertical sectional view illustrating still another modification of my furnace construction.

Referring more in detail to the drawings:

In Fig. 1, wherein I have shown one form of hearth furnace and boiler system embodying the principal novel features of the present invention, 5 designates the furnace chamber and 6 the combustion chamber located above and in direct open communication with the furnace chamber. At the back of the furnace, is a lower masonry wall section 7 and an upwardly continuing but somewhat forwardly offset upper wall section 7x. At the front of the furnace, is a lower, vertical masonry wall section 8 of less height than section 7, and an upwardly continuing and forwardly sloping wall structure 8x. Between the rather closely related wall sections 7 and 8 is a chamber 9, which receives the ashes and non-combustibles from the lower end of the hearth as presently explained.

The hearth, which is designated in its entirety by reference character H, comprises an inclined bank of water-tubes disposed immediately above and supported in part by the inclined wall section 8x. The water-tubes 10, which make up the hearth, are assembled in the same plane, in parallel relationship and closely spaced, as best shown in Figs. 4 and 6. At their upper and lower ends, respectively, the tubes are connected in the boiler circulating system by means of the hearth feeder tubes 13 and riser tubes 14.

It is anticipated, in furnaces where the construction permits, or where it is advisable, that the hearth shall include at each of its opposite longitudinal edges, a plurality of vertically spaced water-tubes 10' in accordance with the showing in Figs. 11 and 12. These tubes are connected at their opposite ends with the boiler circulation preferably by connections with the headers 11 and 12. Their particular purpose is to prevent the adherence of slag to the side walls of the furnace, and also to absorb heat in the fuel bed along the sides of the hearth. These side tubes might be bare, or have fins attached, or might be enclosed in silicon carbide or similar slag resisting blocks.

It is further anticipated that the side wall tube system of the boiler, indicated at 15 in Fig. 1, as well as the front and back water-wall systems, designated at 15a and 15b, shall be connected in the circulatory system and their connection may be accomplished in any suitable manner.

In Fig. 1, the header 12 is shown to be partially enclosed within the lower portion of the section

7 of the back wall, and the tubes 10 of the hearth extend across the top of the ash chamber between the wall sections 7 and 8. At this location, alternate tubes of the hearth are downwardly offset, as is the part 10x, to provide spaces between the tubes through which the ash and other non-combustible materials will be discharged from the lower end of the hearth into the ash chamber.

As one alternative construction for the lower end portion of the hearth, it is shown in Fig. 2 that a header 12a is disposed at the forward side of the wall 8 and the hearth tubes 10 are curved downwardly and forwardly through the wall to connect with the header, leaving the entrance to the ash pit 9 open.

Another alternative design has been illustrated in Fig. 3 wherein the hearth tubes are shown to be curved downwardly and forwardly through the wall 8 to connect with the header 12f located forwardly of the wall as in Fig. 2, and showing also a back wall 7c that is water cooled by use of water tubes 15d connected at their lower ends with a header 12x which is connected in the boiler system, and which is located at the back side of wall 7. In this design, entrance to the ash pit is open.

In each of these alternative designs, the ash and non-combustibles are discharged from the toe of the fuel bed directly into the ash pit. Slag at the discharge end of the hearth is apt to adhere to the exposed fire clay refractories at this location, therefore, it is desirable that this portion of the hearth be protected with a suitable facing material, such as for example, blocks of silicon carbide, known in trade as "Bernitz blocks" or blocks of chrome, cast iron blocks or other material that has proper strength, high thermal conductivity and resistance to clinker adhesion.

Such a facing material has been indicated in Figs. 2 and 3 by reference numeral 18 and it is shown to be applied to the hearth tubes and also to wall surfaces of the ash pit to prevent the adherence of slag thereto. In addition, protection against slagging may be obtained by welding metal strips or fins to the facing.

It is shown in Fig. 1 that the wall section 7x is joined with the wall section 7 by a horizontal ledge 7a formed with a rounded nose 7b facing the hearth. This nose defines the top surface or a rather narrow passage 16 between it and the hearth through which the toe of the fuel bed advances for discharge of ash and non-combustibles to the ash chamber.

Above and across the upper end portion of the hearth is the furnace arch structure 20. This is provided with an opening 21 for the feeding of fuel to the furnace from a fuel storage bin 22. Extending across the arch structure, back of opening 21, is a duct 23 from which pre-heated, over-fire air is supplied under pressure to jets 24 leading downwardly and opening through the arm into the furnace.

Located directly below the hearth H, is a series of plenum chambers 25 from which pre-heated air is supplied, under pressure and in regulated amounts, to the different zones of the hearth as defined by the limits of the individual chambers.

In the present instance there are four plenum chambers, each of which extends to the full width of the hearth. The succession of plenum chambers reaches from the wall section 7 to near the upper end of the hearth. Each chamber 25

is supplied with pre-heated air under pressure from a suitable source of supply, here illustrated as a duct 28, through individual connections 29, each of which connection is equipped with a valve or gate 30, whereby the amount of air admitted to the chamber may be regulated and the pressure of air in the chamber controlled.

Each plenum chamber 25 has a cross-sectional form like that of a V-shaped trough or hopper as seen in Fig. 5, and is open at the top to the under side of the hearth, thus providing that air will be supplied equally to all parts of the hearth zone and that siftings passing through the air passages between the tubes 10 will be collected in the lower portion of the hopper and may be raked out through the cleanouts therein designated at 32.

In the present preferred setting of the hearth, in a furnace using wood waste fuel, its slope is between 40° and 42½°. The degree of slope, however, is determined in accordance with the angle of repose of the particular fuel being used on the grate under burning conditions, and would vary with different fuels. Therefore, it is not intended that the slope be limited to this range of degrees. The tubes 10 used in the hearth have an outside diameter of 3½ inches and are so set as to provide open passages 35 about ½ inch wide between them. These passages 35 constitute about 2.6% of the total hearth area. This should not exceed 5%.

The wood-waste, in its delivery downwardly from feed opening 21, first strikes the upper end portion of the hearth and bounces or slides downwardly therewith toward the lower end, thus gradually building up the fuel bed 36 to the approximate form indicated in Fig. 1. During burning of the fuel bed, the air introduced under pressure through the restricting passages 35, provided by the close spacing of tubes 10 of the hearth, has a jet action that facilitates the downward movement of the bed. As the toe portion of the fuel bed burns away, the ash and non-combustibles pass therefrom to the ash chamber 9 and the bed advances accordingly. The burning of the bed is progressive, since the present manner of feeding the fuel to the hearth avoids the covering of the incandescent material with green fuel. The rate of burning along the fuel bed is regulated and the proper conditions for combustion effected by the controlled rate of feeding of fuel to the hearth and the application of pre-heated forced-draft air to the individual plenum chambers 25 and its injection through the grate passages 35 and fuel bed to the combustion chamber.

It is desirable in some instances that the upper zone of the hearth be left uncovered by the fuel bed to more or less extent in order that pre-heated over-fire air may be supplied from the corresponding plenum chamber to supplement that supplied through the other overdraft air supply jets.

To insure complete and maximum burning rate of fuel at the toe of the fuel bed, I provide air jets 40 extended through the wall section 8 and directed upwardly into the top portion of the ash chamber. Also, I provide air jets 41 directed downwardly through the shelf 7a into the open space, directly above the ash chamber 9. These two series of air jets 40 and 41, are supplied with pre-heated air under pressure, through connections 42 and 43 leading thereto from the air duct 28, and equipped with suitable gates or valves 44 for regulating the air delivery.

The fuel bin 22 contains, at the bottom thereof, one or more parallel fuel feed chain belts 50, operating about sprocket wheels 51 and 52 on driven cross shafts 53 and 54. These belts deliver fuel from the bottom of the supply bin into a hopper 56 that discharges directly into the opening 21 through an air tight connection. Hingedly suspended in the hopper outlet is a gate 57, fixed to a horizontal hinge shaft 58. The shaft 58 is rotatably mounted and a weighted lever arm 59 is so fixed thereto as to normally retain the gate in a position closing the hopper outlet but permitting the gate to swing downwardly to an open position under weight of fuel delivered thereagainst. This normally closed gate prevents furnace gasses passing out through the passage 21 and also is a safeguard against "blowback".

The feeding of fuel by this means and through the valve controlled passage prevents any undesirable syphoning of cold air through the passage and eliminates the intaking of cold air with the fuel charge.

In Fig. 9, I have illustrated a hearth furnace embodying the previously described features of the present invention therein, and showing an alternative fuel feeding mechanism. In this design, the hearth, designated by reference character H', is substantially like that previously described in that it comprises a bank of water tubes 18a, connected at upper and lower ends to headers 11a and 12a which, in turn, are suitably connected in the boiler circulatory system as was previously explained. In this furnace, the arrangement of plenum chambers, and the control and delivery of pre-heated, forced-draft air thereto is by means substantially like that already described. Therefore, these parts have been given reference numbers corresponding to those applied to like parts in Fig. 1. The means shown in Fig. 9 for feeding the fuel to the furnace will be now described.

The furnace chamber designated by numeral 60 is enclosed by a back wall 61, front wall 62 and side walls 63. The hearth H' and a sloping section 61' of the back wall of the furnace converge downwardly to an ash trough 65. The hearth tubes connect to the header 12a in the manner like that of Fig. 2 previously described.

Overlying the upper end portion of the hearth and extending forwardly from the wall 62 as a shelf is a furnace arch structure 66. Formed through this structure is a fuel feed inlet 68 to which fuel may be supplied by any suitable means, preferably, by means like or of the character of that disclosed in Fig. 1.

Mounted adjacent the fuel inlet, is a guide bearing 71 in which a ram or plunger 72 is reciprocally contained. The ram is operable by means of a pitman rod 73, connected eccentrically to a driven wheel 74, to push the fuel, as fed through the inlet onto the upper end of the hearth, downwardly along the hearth for burning. The slope of the hearth is slightly less than the angle of repose of the fuel that is to be burned thereon.

In this design, over-fire air is admitted through jets 75 opening into the furnace through the arch structure 66. The ducts 75 lead from a header 78 and this may be supplied with pre-heated air from any suitable source of supply. Also, air jets 80 enter the ash pit beyond the lower end of the hearth to supply pre-heated air to insure maximum burning of the toe portion

of the fuel bed before it is discharged into the ash pit.

In the furnace of Fig. 9 I have indicated use of auxiliary fuel by the showing of oil burners 90. These are directed into the combustion chamber through openings 91 in the back wall 61. Gas or powdered coal might likewise be employed as supplemental or auxiliary fuel.

It is to be understood that a similar use of auxiliary fuel might be made in the furnace of Fig. 1. In any such use of auxiliary fuel, the burners are applied in the central portion of the combustion chamber in order that the products of combustion from the wood refuse will be compelled to pass through the zone of high temperature and turbulence, insuring complete combustion of all gases.

In a furnace where either oil, gas or powdered coal is used as auxiliary to wood waste fuel, the maximum furnace temperature is obtained by having the wood waste fuel subject to the radiant heat from the combustion of the auxiliary fuel as will be the case in the furnace of Fig. 9. In cases where the auxiliary fuel is a very minor portion, or where operation for extended periods will be without the aid of auxiliary or supplement fuel, then it is proposed to have a large portion of the hearth under a refractory arch which will reflect heat on the fuel bed. Furthermore, there should be nothing to prevent the fuel bed being subjected to maximum, radiant heat from the flame as it occurs in the combustion chamber. Such a furnace arrangement has been illustrated in Fig. 10 wherein the hearth H2 is shown to extend at its lower end under the overhanging refractory arch structure 82. Where the fuel contains high percentage of moisture, it becomes necessary to have refractory walls on the sides and back of the combustion chamber in the intermediate proximity of the hearth to further reflect heat on the fuel bed for the purpose of driving off the moisture and distilling the volatiles. Such a refractory area is designated in the triangle 85 in Fig. 1.

As an alternative hearth construction, it is anticipated in lieu of the close spacing of tubes 10, as shown in Fig. 6, that they be spaced farther apart and the intervening spaces be blocked off by lugs 99 welded to the side walls of adjacent tubes, as shown in Fig. 7 wherein the lugs of adjacent tubes are aligned. Another arrangement of lugs 99 is that shown in Fig. 8 wherein those on adjacent tubes are staggered and overlapped. The area of air passages thus provided should not, in any arrangement, exceed 5% of the hearth area in order to insure necessary restriction to air flow.

In Fig. 12 I have shown another modification of furnace construction embodying novel features of the present invention. In this, the sloping water-cooled hearth, designated at H3, is shown to be connected at upper and lower ends in the boiler circulation through the mediacy of headers 11c and 12c. The hearth area is divided into a succession of zones of control by the plenum chambers 25 in the manner previously described. Opposite the hearth is an inclined, water-cooled wall, 110, and above the higher end of the hearth is a refractory arch construction 115 whereby heat is caused to be reflected to effect moisture evaporation from the entering fuel. Fuel is admitted through opening 118 and ashes are discharged into pit 120. Side walls of the furnace are here protected against slag adhesion by side wall tubes 125 connected at their ends in the

boiler circulation. Auxiliary fuel burners are indicated at 130.

Assuming that a furnace has the novel features of construction of the present invention embodied therein and that the rate of feeding of fuel into the furnace is regulated in such manner as to maintain a fuel bed of proper depth and desired extent along the hearth, and the pre-heated air is being supplied under pressure to the various plenum chambers and jets as required for best burning efficiency, the following conditions and advantages will be obtained.

First, a large area of fuel will be exposed to the furnace temperature. The manner of feeding the fuel to the hearth will prevent the green fuel from covering the fuel previously fed. Injected air will cause the fuel bed to move gradually downward from a zone of distillation to a zone in which only the fixed carbon remains. Complete burning is insured by injecting air at the toe of the fuel bed. Ash and non-combustible material will be discharged into the ash chamber where slag adherence is prevented by use of proper wall lining.

By reason of controlled admittance of pre-heated, forced-draft air to the individual plenum chambers, a zone control can be established as may be required to best suit the fuel being used and the depth of fuel bed at the various zones.

Zone control makes possible the forcing of pre-heated air in regulated amounts and pressures through the green fuel to drive off moisture and volatiles. Additional air can be so injected in regulated amount and pressure through the zone of incandescent carbon that a mixture of carbon monoxide and carbon dioxide is formed; the former being converted into carbon dioxide in the presence of the pre-heated, over-draft air admitted through the various jets or through the partly uncovered hearth at the uppermost zone.

The manner of feeding the fuel to the hearth prevents entrance of air with the fuel or the syphoning or injecting of cold air into the furnace through the feed opening. By incorporating the tubes of the hearth in the boiler circulatory system the heat that is absorbed by them, either from the preheated air or from the fuel, is usefully employed in the evaporation of the boiler water.

Limiting the air openings or passages through the inclined hearth to less than 5% of the hearth area and the provision of zoned air supply for the controlled application of pre-heated air to the different parts of the fuel bed decreases furnace upkeep and improves the rate of burning.

The water cooled grates generally in use, limit the temperature to which the cooling medium can be raised. It must be kept below the temperature of atmospheric boiling and unless distilled water is used, must be kept below the temperature at which scale forming matter will deposit, in order to avoid formation of scale within the grate. The present system, characterized by the connecting of the water-tubes of the sloping hearth as an extension of the water-wall surface in the boiler circulatory system, not only permits the cooling of the hearth by water at higher temperatures but also effects such cooling at a constant temperature corresponding to the steam temperature of the boiler. It also supplies all heat taken from the fuel to the boiler at higher temperature range where it can be gainfully employed.

Having thus described my invention, what I

claim as new therein and desire to secure by Letters Patent, is—

1. In a furnace and boiler combination, a water-cooled hearth comprising a sloping bank of bare water-tubes forming a surface for the support and burning of a fuel bed thereon; said tubes being parallel and extended in the direction of slope of the hearth and closely spaced to provide restricted air passages between them, means connecting the tubes of the hearth with the circulatory system for flow of boiler water therethrough, the lower end portions of alternate water-tubes being offset to provide spaces therebetween, an ash pit below and under the lower end of said hearth, means for injecting a controlled amount of air into said ash pit below the lowest level of said hearth for movement of air upwardly through the ash discharging through the spaces in the end of said hearth, means at the under side of the hearth dividing the hearth area into a succession of individual zones of control and means for supplying air under pressure and in regulated amounts to the individual zones for injection into the furnace through the restricted passages.

2. A furnace and boiler combination as recited in claim 1 wherein the intertube air passages are uniformly distributed over the hearth area and comprise less than five percent of the total fuel bed area of the hearth.

3. In a furnace and boiler combination; a water-cooled hearth comprising a sloping bank of bare tubes connected in the boiler circulatory system for flow of boiler water therethrough; said tubes being extended in the direction of slope and spaced to provide restricted air passages between them, means at the higher end of the hearth for the supplying of fuel thereonto to maintain a fuel bed of predetermined depth that is caused to progress downwardly along the

5

hearth as it burns, archs overlying the upper and lower ends of said hearth respectively, air nozzle means for supplying overfire air through each of said arches in a downward direction toward the bed of fuel maintained at the end portions of said hearth, a succession of plenum chambers arranged along the hearth at its under side, and open thereto, and dividing the hearth area into a succession of individual zones of control, a source of supply of pre-heated air, and means for effecting a controlled admittance of pre-heated air from said source of supply to each of the individual chambers for flow therefrom to the furnace through the hearth passages and fuel bed overlying the chamber.

4. A furnace and boiler combination as recited in claim 3 designed for the burning of moist hogged fuel, and wherein the hearth is sloped at an angle within a range of 40° to $42\frac{1}{2}^{\circ}$ relative to a horizontal plane.

HENRY W. BEECHER.
